Robert H. Hornam

UNITED STATES PATENT OFFICE.

WILLIAM P. CUNNINGHAM, OF NORRISTOWN, PENNSYLVANIA.

MEANS FOR HOLDING SECTIONAL MOLDS.

1,295,704.

Specification of Letters Patent. Patented Feb. 25, 1919.

Application filed August 30, 1918. Serial No. 252,118.

To all whom it may concern:

Be it known that I, WILLIAM P. CUNNINGHAM, a citizen of the United States, and a resident of Norristown, county of Montgomery, State of Pennsylvania, have invented certain Improvements in Means for Holding Sectional Molds, of which the following is a specification.

One object of my invention is to provide suitable means for holding sectional molds in proper relation to each other during the process of pouring.

A further object of the invention is to provide means for holding sectional molds so that they can be assembled in series for continuous casting.

The invention is particularly adapted to hold sectional molds in which continuous chains are cast, but it will be understood that the invention can be used for molding other forms, if found desirable.

In the accompanying drawing:—

Figure 1, is a perspective view of one element of my improved means for retaining sectional molds during the process of casting;

Fig. 2, is a side view, showing the series of elements connected together; and

Fig. 3, is a sectional view on the line 3—3, Fig. 2, showing the mold in position ready for pouring.

In an application for patent filed by me on the 9th day of July 1918, Serial No. 244,034, I have described a sectional mold for casting continuously independent links, especially in the manufacture of anchor chains. These molds are made in quarter sections and the quarter sections are assembled in pairs side by side, the pairs being alternately arranged so as to make a series of molds which, when the metal is poured into them, will produce castings in which the links are enchain'd.

My present invention relates to certain improvements in means for retaining these sectional molds in position during the casting operation so as to insure accuracy in the casting and to hold the molds after the metal has been poured and during the cooling operation. The elements of the holding means can be arranged end for end and mounted on a casting floor so that the link castings can be poured independently, if desired, or they can be mounted on a movable carriage which will pass the pouring point as it travels, so that the molds can be put in

position at one point and the metal can be poured at another point. Then the molds can be broken at another point, after the metal has set, and the holders returned to the first position, while the cast chain will pass out continuously and may thus be made of any length desired.

1 is the base section of one of the elements, having end plates 2 and an intermediate supporting plate 3 forming a support for the mold, the end plates forming the means whereby the two adjoining elements can be secured together. The base has a V-shaped recess 4 therein to receive the bottom portion of the mold sections 5, and these mold sections are rectangular in cross section, with the exception of the top which is flat, and the two side clamps 6 of the elements are secured by bolts 7 to the base, as shown, and bear upon the two inclined upper surfaces of the mold section, clamping the mold sections firmly in position on the base.

At the center portion of the base is a groove 8 and at each side the clamps 6 are cut away so as to form grooves 9, and these three grooves allow the edges of the molds to rest clear of the structure so that it will be firmly held by the clamps, thus rigidly holding the mold sections in position. Each of the end plates 2 and 3 of the elements is notched at 10 at each side, as shown, so as to register with guides on the carriers, or other movable supports, so as to prevent strain being placed on the securing bolts, which connect the elements together, and also to prevent the elements moving out of line one with another. The clamps are provided with ribs 11 at intervals to reinforce them, and the base portion is also provided with longitudinal ribs 12 for a like purpose.

The mold sections are made as clearly shown in Figs. 1 and 3, each section forming a quarter of a mold for two chained links of a chain. These sections are then placed in the base section and clamps 6 are secured to the base section on each side and bear upon the upper inclined portions of the mold sections, holding them firmly in position. The mold sections are located in one element after another and the elements are secured together as described and are moved forward, being mounted on suitable carriages which carry the molds past the pouring station where the metal is poured into each individual mold for a link. The elements may be made stationary and the pouring

device may be moved so as to pour the metal for one link after another.

After the metal has become sufficiently set, the clamp plates are removed and the 5 mold is destroyed, leaving the enchainged link intact, and the base section of the element is removed and returned to the original station, where it is again assembled in a series and another set of molds mounted in 10 it, the chain passing from the molds to the finishing room where it is tested and made of any length desired. This construction for the support of the mold insures accuracy in the mold and the means for readily han- 15 dling the molds without the liability of fracture.

I claim:-

1. In apparatus for holding sectional molds during the process of casting, the 20 combination of a series of base sections shaped to receive the lower portion of a series of molds; clamp plates secured to the base sections for securing the molds firmly thereto, the base sections being shaped at 25 each end so that the sections can be placed end to end; and means for securing the

several base sections together so as to bring the molds of the several sections into alinement.

2. The combination in apparatus for holding 30 sectional molds during the process of casting, said apparatus consisting of a base having a V-shaped recess therein and having end plates so located that the end plate of one element can be secured to the end 35 plate of another element; and clamp plates for clamping the sectional mold to the base.

3. The combination in means for holding 40 sectional molds, of a base having a V-shaped recess therein extending throughout its 45 length and having end plates whereby a series of elements can be placed end to end and bolted so as to bring the grooves into alinement; a clamp plate located on each side of each base and rigidly secured thereto; the clamp plates being at right angles to the walls of the V-shaped groove in the base, the clamp plates being spaced apart so as to expose the pouring openings of the molds.

In witness whereof I affix my signature. 50

WILLIAM P. CUNNINGHAM.
